UNITED STATES PATENT OFFICE.

ELEAZER KEMPSHALL, OF WASHINGTON, DISTRICT OF COLUMBIA.

DESIGN FOR A GOLF OR PLAYING BALL.

47,159.

Specification for Design.

Patented Mar. 30, 1915.

Application filed January 6, 1915. Serial No. 777. Term of patent 14 years.

To all whom it may concern:

Be it known that I, ELEAZER KEMPSHALL, a citizen of the United States, residing at Washington, in the District of Columbia, have invented a new, original, and ornamental Design for Golf or Playing Balls, of which the following is a specification, reference being had to the accompanying drawing, forming part thereof.

Figure 1 is a plan view and Fig. 2 is a side

view of a golf or playing ball, showing my new design.

I claim:

The ornamental design for a golf or playing ball, as shown.

ELEAZER KEMPSHALL.

Witnesses:

HUGHES OLIPHANT,
M. A. DEES.
